CLAIM

The ornamental design for a hair iron, as shown and described.

DESCRIPTION

FIG. 1 is a front, left side and top side perspective view of a hair iron of our new design, in its closed configuration. FIG. 2 is a front, right side and bottom side perspective view thereof.

FIG. 3 is a front view thereof.

FIG. 4 is a rear view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a front, left side and top side perspective view of the hair iron of our design, in its opened configuration.

FIG. 10 is a front, right side and bottom side perspective view of a hair iron, of our new design, shown in an open configuration.

FIG. 11 is a front elevation view thereof.

FIG. 12 is a rear elevation view thereof.

FIG. 13 is a left side elevation view thereof.

FIG. 14 is a right side elevation view thereof.

FIG. 15 is a top plan view thereof; and,

FIG. 16 is a bottom plan view thereof.
